UNITED STATES PATENT OFFICE

2,280,381

SHOE RACK

Harold G. Davis, Denver, Colo.

Application May 28, 1940, Serial No. 337,597

6 Claims.

(Cl. 211—35)

This invention relates to a portable shoe rack and has for its principal object the provision of a neat, highly efficient, collapsible device, which can be conveniently carried in a suitcase or traveling bag; which can be quickly and easily applied to either face of any desired door, without the use of tools; which will maintain itself and the shoes therein securely in place on the door; which will be adaptable to doors of any size; and in which shoes of any style or type may quickly and easily be placed to be stored and protected until ready for use.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view illustrating the improved shoe rack in place on a door.

Fig. 2 is a face view of the rack illustrating, in solid line the rack in the contracted position and, in broken line, the extended position thereof.

Fig. 3 is a plan view of the rack as shown in Fig. 2.

Fig. 4 is a longitudinal, horizontal section through the rack bar in the contracted position.

Fig. 5 is a detail, perspective view of one of the rack bar hangers.

A fragmentary portion of a typical door is illustrated at 10 in Fig. 1.

The improved shoe rack employs a hollow, telescoping rack bar consisting of an inner tube 11 and an outer tube 12. The tubes are preferably formed of sheet metal rolled into cylindrical shape and terminating at their outer extremities in projecting tabs 13, by means of which they are secured to supporting brackets 14. The inner extremity of the outer tube 12 is reinforced by means of a suitable reinforcing ring 15.

The outer tube 12 is continually urged over the inner tube 11 by means of a tension spring 16. The two extremities of the tension spring are extended through perforations in the supporting brackets 14 and are turned to form hooked locking extremities 17.

The supporting brackets 14 extend forwardly to the door and are turned oppositely outward at their bottoms to form base portions 18 which extend at right angles to the plane of the brack-

ets and parallel to the axis of the rack bar to the side edges of the door. The outer edges of the base portions are turned sharply forward at right angles to form flanges 19. The forward edges 5 of the flanges are turned inwardly, parallel to the base portions 18 and are serrated to form a plurality of relative short, sharp teeth 20.

For the purpose of illustration, it was necessary to magnify the size of the teeth. In the 10 actual construction the teeth do not exceed $\frac{3}{16}$ of an inch and are preferably not over $\frac{1}{8}$ of an inch in length.

In applying the rack bar to the door, the 15 bracket members are taken in the two hands and the bar is extended to exceed the width of the door. The base portions 18 of the brackets are then placed against the face of the door adjacent the side edges thereof and the brackets are released. This allows the spring 16 to pull the 20 two flanges 19 against the opposite side edges of the door to cause the teeth 20 to bite into the side edges thereof. Ordinarily, no further installation steps are required. If the door, however, is of exceedingly hard wood or if the device 25 is to be left permanently in place, the flanges 19 may be lightly tapped with the heel of a shoe to drive the teeth 20 securely into the wood of the door.

It is desired to call attention to the 30 advantages of the base portions 18 of the bracket members. When the device was first constructed, the bracket members extended inwardly to the teeth portions thereof without the offset and the results were entirely unsatisfactory. In the first place, it was difficult to accurately position the device on the door; in the second place, the door could not be opened but a little way until the bracket on the hinge side thereof would strike the door casing and dislodge the entire rack; and in the third place it would support but very little weight before the teeth would be pulled from the wood. It was found, however, that after base portions of sufficient width were placed on the bracket members, all of the above 35 difficulties were eliminated and the device would support a weight of 100 pounds at the mid-portion of the rack bar without pulling the small teeth from the wood.

The above results are believed to be due to a 40 unique lever action of the base portions. When weight is applied, the upper inner corners of the base portions tend to pull away from the door and in so doing attempt to shorten the distance between the bracket members and the flanges 45 19. This tendency acts to pull the teeth inward-

ly into still firmer engagement with the door so as to eliminate any tearing-out action.

The device as thus far described makes a very efficient shoe rack for use on any door. The shoes are simply slipped toe downwardly behind the rack bar, as illustrated in Fig. 1.

Provision is also made for protecting both the door and the shoes, this is accomplished by forming a telescoping housing of relatively stiff material such as heavy cardboard. The housing is formed in two sections, each section preferably consisting of a single sheet of material which is cut and folded to form a backboard 21, end plates 22, and a top cover 23. Both the end plates and the top covers are hingedly attached to the back boards 21. The back board of one section slides over the back board of the other and the top cover of one section slides over the top cover of the other to allow the entire housing to expand or contract as desired. The two back boards are held in alignment with each other by means of U-shaped clips 24 secured near the extremity of each back board and over-lapping the extremity of the adjacent back board.

The two end plates 22 are notched, as shown at 25, to receive the rack bar. After the rack bar has been placed in position on a door, the housing structure is slipped behind the bar and the end plates are turned out with their notches engaging the rack bar and the entire device is expanded to the full length of the bar, when it will appear as in Fig. 1.

The back boards serve to protect the door from damage by the shoes and the top covers 23 serve to conceal and protect the shoes from dust, etc. When not in use, the entire enclosing housing can be opened out as a flat sheet so that it can be easily placed in the bottom of a suitcase or trunk.

It is desired to call attention to the fact that the bracket members are formed of relatively thin sheet metal and are channelled as illustrated to provide stiffness and rigidity. The thinness of the metal flanges 19 allows them to fit into the space or crack between the door and its frame and also to pass between the door and the door stop so as not to interfere with the ordinary uses of the door.

This thinness is absolutely necessary since these spaces about the door are exceedingly limited. Since it is necessary to use very thin material a considerable problem was presented to produce a supporting structure of sufficient strength and rigidity to serve the purpose intended.

This problem was solved by the specific design of the brackets, including the channelled bracket structure, the base portions, the narrow flange 19 and the short teeth 20.

The top cover of the housing may be brought further down if it is desired to more completely conceal the shoes.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A shoe rack for attachment to a door comprising: a telescopedically expandable rack bar; a bracket member secured to each of the outer extremities of said rack bar; a tension spring within said rack bar constantly urging it toward its

contracted position; a base portion on each bracket member extending outwardly at right angles thereto and parallel to the axis of said rack bar to lie against the face of the door; a flange portion extending forwardly from the outer edge of each base portion and at right angles thereto to engage the side edges of said door; and imbedding means on the side edges of said flanges to be held imbedded in said door by the action of said spring.

2. A shoe rack for attachment to a door comprising: a telescopedically expandable rack bar; a bracket member secured to each of the outer extremities of said rack bar; a tension spring within said rack bar constantly urging it toward its contracted position; a base portion on each bracket member extending outwardly at right angles thereto and parallel to the axis of said rack bar to lie against the face of the door; a flange portion extending forwardly from the outer edge of each base portion and at right angles thereto to engage the side edges of said door; and an inwardly turned toothed edge on each of said flanges, said toothed edges extending parallel to said base portion and positioned so as to be held imbedded in the side edges of said door under the action of said spring.

3. A shoe rack for attachment to a door comprising: a telescopedically expandable rack bar; a bracket member secured to each of the outer extremities of said rack bar; a tension spring within said rack bar constantly urging it toward its contracted position; a base portion on each bracket member extending outwardly at right angles thereto and parallel to the axis of said rack bar; a flange portion extending inwardly along the outer edge of each base portion and at right angles thereto to engage the side edges of a door; imbedding means on said flanges to be held imbedded in said door by the action of said spring; and a telescoping enclosure held against said door by said rack bar, said enclosure being provided with notches receiving the rack bar whereby the enclosure is supported.

4. A shoe rack for attachment to a door comprising: a telescopedically expandable rack bar; a bracket member secured to each of the outer extremities of said rack bar; a tension spring within said rack bar constantly urging it toward its contracted position; a base portion on each bracket member extending outwardly at right angles thereto and parallel to the axis of said rack bar; a flange portion extending inwardly along the outer edge of each base portion and at right angles thereto to engage the side edges of a door; imbedding means on said flanges to be held imbedded in said door by the action of said spring; and a telescoping enclosure held against said door by said rack bar, said enclosure having forwardly extending end plates, said end plates being notched to receive said rack bar to hold said enclosure in place on said door.

5. A shoe rack for attachment to a door comprising: a telescopedically expandable rack bar; a bracket member secured to each of the outer extremities of said rack bar; a tension spring within said rack bar constantly urging it toward its contracted position; a base portion on each bracket member extending outwardly at right angles thereto and parallel to the axis of said rack bar; a flange portion extending inwardly along the outer edge of each base portion and at right angles thereto to engage the side edges of a door; imbedding means on said flanges to be held imbedded in said door by the action of said spring;

a telescoping enclosure having forwardly extending end plates, said end plates being notched to receive said rack bar to hold said enclosure in place on said door; and a telescoping, hinged lid on the enclosure to allow shoes to be inserted behind said rack bar.

6. Means for attaching a spring actuated telescopically contractable cross bar to a door so as to provide a supporting rack thereon which will not interfere with opening and closing said door comprising: a supporting bracket secured to each extremity of said rod and extending to the face

5 of said door to points inwardly spaced from the side edges thereof; a base portion extending from the door extremity of each bracket, said base portions extending oppositely outward from each other to the two side edges of said door; a flange on the outer edge of each base portion extending forwardly therefrom to overlie the opposite side edges of said door; and inwardly directed door engaging edges on said flanges extending into the opposite side edges of said door.
